CONTROL LEVER FOR GARDEN TYPE
UMBRELLAS

Heinz Weber, Hilden, and Peter Stamm, Witzhelden, Germany, assignors to Telesco Brophey Limited, East Montreal, Quebec, Canada

Filed Aug. 7, 1972, Ser. No. 278,433

Term of patent 14 years

Int. Cl. D3—03

U.S. Cl. D88—3 A

FIG. 1

FIG. 2

FIG. 3

FIG. 4

FIG. 1 is a perspective view of a control lever for garden type umbrellas showing our new design;

FIG. 2 is a front elevational view thereof, the rear being identical therewith;

FIG. 3 is a side elevational view thereof, the opposite side being identical therewith; and

FIG. 4 is a cross sectional view thereof as taken on line 4—4 of FIG. 2.

We claim:

The ornamental design for control lever for garden type umbrellas, as shown.
